CLAIM

The ornamental design for a microfluidic chip, as shown and described.

DESCRIPTION

FIG. 1 is a top front right perspective view of a microfluidic chip showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof; and,

FIG. 7 is a front elevation view thereof. ps The broken lines are included for the purpose of illustrating portions of the microfluidic chip that form no part of the claimed design.
